J. CASSADY,
CIRCULATING AIR HEATER,
APPLICATION FILED DEC. 29, 1919.

1,402,728.

Patented Jan. 3, 1922.

FIG. 3.

INVENTOR

John Cassady

BY

Carl M. Crawford

ATTORNEY

UNITED STATES PATENT OFFICE.

JOHN CASSADY, OF RITZVILLE, WASHINGTON, ASSIGNOR TO CASSADY SPECIALTY COMPANY, OF RITZVILLE, WASHINGTON, A CORPORATION OF WASHINGTON.

CIRCULATING AIR HEATER.

1,402,728.

Specification of Letters Patent.

Patented Jan. 3, 1922.

Application filed December 29, 1919. Serial No. 347,977.

To all whom it may concern:

Be it known that I, JOHN CASSADY, a citizen of the United States, residing at Ritzville, in the county of Adams and State of Washington, have invented new and useful Improvements in Circulating Air Heaters, of which the following is a specification.

This invention relates to improvements in heaters and has to do more particularly with 10 circulating air heaters.

One of the objects of this invention is to provide an air heater which may be applied as an attachment to any kind of a stove having a stove top portion from which the 15 heated ascending air may be received into the heater, the device of my invention being particularly adapted for use on oil, gas, gasoline, electric or other types of ranges.

A further object of the invention is to 20 collect the relatively colder air near the floor of the room and utilize such air as an air feed to the heater so that as the air is heated it will be discharged near the top of the heater thereby creating a circulation of 25 air in the room from the floor plane to an elevation slightly above the breathing zone of an upright adult of the average height. Thus, that area of the room which, for the purpose of illustration might be 30 termed the "habitable portion," will be warmest, irrespective of the temperature near the ceiling zone.

My invention also involves the novel feature of a heater which is partly supported 35 on the stove or range and partly on the floor, thereby insuring stability of the heater while in position, and rendering it easy to apply or remove from position without any attaching device. In this connection, it is 40 a feature of my invention to provide a heater of this character which is adjustable whereby it may be applied to ranges or stoves of different heights.

It is a further feature of my invention to 45 separate the incoming cold air entering the heater, from the entering heated air ascending from the stove or range, in such a manner, that the entering cold air will not objectionably cool the heated air, and this feature of the invention includes an improved 50 spreader for the entering cold air which is itself heated by the entering hot air ascending into the heater from the stove, whereby the spreader will to a great extent act as 55 a pre-heater for the entering cold air, this

feature being embodied in a spreader or guard structure which is disposed in the path of the incoming heated air.

Other objects and features of my invention will be more fully described in connection with the accompanying drawing and will be more particularly pointed out in and by the appended claim.

In the drawing:—

Figure 1, is a view in side elevation of 65 my improved heater applied to a gas or oil range.

Figure 2, is an enlarged vertical sectional view of the heater removed from the range.

Figure 3 is a sectional view on line 3—3 70 of Figure 2.

Like characters of reference designate similar parts throughout the different parts of the drawing.

As shown, my invention is applied to the 75 grid 1, of a gas, oil or other stove 2, although its application and utility is not limited to these particular types of stoves as it may be applied to any stove having a heating stove top.

My invention includes a heating drum 3, the upper portion of which is preferably closed by a lid 4. The drum 3 is cylindrical and I preferably taper the upper portion thereof, as indicated at 5. In the tapered 85 portion 5 is a plurality of hot air discharge openings 6, the aggregate capacity of which will be considerably less than the capacity of the major portion of the drum for conveying hot air. Thus to a certain extent, 90 the constriction afforded by these openings 6 will be sufficient to retain and restrict the passage of the hot air from the drum 3 not only long enough to permit the air to be heated but also to permit the hot air to 95 thoroughly heat and maintain the drum heated so that the latter will radiate heat to the surrounding air. Furthermore, the drum 3 is of sufficient height to dispose the discharge openings 6 substantially above 100 the head of an upright adult so that the heated air will be discharged at such an elevation in the room that it will be effective to that area which is mostly inhabited by the human being.

The lower rim 7, of the drum 3, is adapted to seat on a stove grid and could, if slightly elevated, be seated upon the top of an ordinary cooking stove, it being the function of the lower open end 8 to receive 110

heated air from a stove, the device of my invention being strictly an attachment heater.

It is the theory of my invention to take 5 the colder air, or that air nearest the floor, as its intake air supply so that in the shortest possible time that zone or area of air which is coldest, and which is nearest the floor, will be taken up and heated with a view of 10 quickly promoting the descent of the warmer air toward the floor level.

Thus my invention includes a cold air inlet pipe 9 which as shown delivers to the drum 3 preferably laterally thereof, the opening 15 10, for the cold air, being nearly adjacent the opening 8, for the heated air. Furthermore, by branching off the inlet pipe 9 from the drum 3, the device of my invention becomes 20 readily adaptable for application to a stove without requiring any modification of the latter or any attaching devices whatsoever. Thus while the drum 3, overhangs the grid, the cold air pipe 9 extends downwardly at one side of the stove.

25 In view of the fact that different makes of stoves have different heights from the floor 11, I desirably incorporate an adjusting feature in the device of my invention so that the latter will not have to be modified for application to different stoves. Thus 9, designates the upper section of the cold air pipe and 12 designates a lower section which adjustably telescopes the upper section. A device 13, 30 which may be a simple form of band clamp 35 adapted to be tightened by a screw 14, may serve to secure the pipe sections in extensible or contractible positions of adjustment. The lower pipe section 12 is provided with legs 15 to support the lower end 16, of section 40 12, at such an elevation above the floor 11 as to readily permit of a cold air intake as indicated by the arrows 17. These legs 15 perform a further function in that they support the heater, or assist in supporting the 45 heater so as to render the latter stable in its position upon the stove. In the absence of a floor engagement, and because of the cold air pipe, the center of gravity of the heater would be shifted in such a manner as to 50 cause the heater to be readily overturned. With the adjusting device shown, the floor supporting engagement of the cold air pipe can be so nicely adjusted with respect to the 55 engagement of the rim 7 on the stove that the pipe 9 will readily sustain the heater in position.

It is a feature of my invention that while I specifically admit the cold air at a point very 60 nearly adjacent the hot air intake, still, I do not permit intimate and immediate mixture of the cold and hot air. Thus it is a feature of my invention to provide a guard which serves to separate the cold from the hot air for a short period, and this feature of my invention is further developed by con-

structing the guard so that it will function as a spreader for the cold air to widely disperse the same. An additional feature of this guard consists in disposing the same in such relation to the incoming hot air that it 70 will be heated by entrance of the latter so that when the cold air strikes this guard the latter will function to slightly heat as well as to spread the incoming cold air.

As illustrated, this feature of my invention 75 is embodied in a truncated cone 18 which extends from the rim 7 upwardly into the drum 3 and the contraction of which is such that the hot air, or a portion thereof, from the stove burner, will impinge upon the guard 80 18, as indicated by the arrows 19. Furthermore, the top 20 of the guard 18 is slightly higher than the top of opening 10, so that as the hot air expands upon its discharge from the guard 18, it will be delivered toward the wall of the drum 3 at a point above the incoming cold air entering through opening 10. Thus there will be a very slight pressure of the hot air seeking egress from the contracted end 20 which will greatly 90 promote the air flow.

It will now be seen how the guard 18 acts as a spreader and a heater since a portion of the air passing through pipe 9 will flow against the guard, as indicated by arrow 21, 95 and thence upwardly. In its engagement with the guard, the cold air will be heated slightly, sufficiently to remove the chill thereby avoiding the disadvantage of quickly lowering the temperature of the interior of the 100 drum. By reason of the fact that the device of my invention is disposed directly upon the stove, a great deal of the heat therefrom will be transmitted directly to the drum and the guard.

105 It is believed that my invention will be fully understood from the foregoing description, and while I have herein shown and described one specific form of my invention, I do not wish to be limited thereto except for 110 such limitations as the claim may import.

I claim:—

In a circulating air heater attachment for application to a stove top, a hollow drum having the greater portion of its upper interior free from obstruction whereby the ascending cold and hot air may freely mix, the drum having an open bottom adapted to be supported on the stove top to receive the heated air therefrom, a cold air pipe delivering to said drum laterally through the latter and at the lower end thereof, and a truncated conical guard having its base merging into the lower end of said drum and extending upwardly in said drum to a height slightly 125 above the cold air pipe and the converging guard forming with the drum an annular cold air inlet chamber and the guard deflecting the cold air laterally and upwardly as the cold air enters said drum, the converging 130

guard contracting the ascending hot air flowing therethrough and thereby heating said guard to warm the cold air as the latter engages said guard, whereby the cold and hot air will freely mix as they ascend in the upper free portion of the drum, and said drum having outlets at its upper end of re-

duced discharge capacity with respect to the inlet capacity of the open bottom to increase the mixing and heating action of the 10 unobstructed portion of said drum.

In testimony that I claim the foregoing as my own, I hereby affix my signature.

JOHN CASSADY.
